UNITED STATES PATENT OFFICE

STANLEY H. BARROWS, OF CHICAGO, ILLINOIS, ASSIGNOR TO CALIFORNIA CHEMICAL CORPORATION, OF PORTERVILLE, CALIFORNIA, A CORPORATION OF ILLINOIS

CARPET TACKING STRIP

Original application filed January 27, 1927, Serial No. 163,915. Divided and this application filed April 19, 1928. Serial No. 271,171.

When it is desired to use a carpet or the like over a cement or stone floor, etc., a fundamental difficulty has been presented in the lack of any surface suitable to tack to, 5 and floor coverings have been used under such conditions without satisfactory fastening. An adequate provision for such a situation generally is accordingly highly desirable.

10 To the accomplishment of the foregoing and related ends, the invention, then, consists of the features hereinafter fully described, and particularly pointed out in the claims, the following description and the 15 annexed drawings setting forth in detail but a few of the various ways in which the principle of the invention may be employed.

In said annexed drawings:—

Fig. 1 represents a sectional detail of one 20 embodiment of the invention; and Fig. 2 is a similar view of a modified construction.

Referring more particularly to the drawings, there is shown an under support or under flooring 1 of non-wooden character, 25 for instance of concrete or fireproof slab construction, and in relation with a wall 2. Upon such non-wooden support, there is a nail-penetrable element or strip 3, being secured to the under support by cementitious 30 adhesion.

While in some instances such nail-penetrable strip may consist of wood, more advantageously it may be of a cementitious composition, suitably nail-penetrable by the 35 inclusion of proper filling constituents. Such cementitious composition strip may be preformed and then be secured in place by cement *c*, but preferably I form the strip directly in place by casting or molding the 40 cementitious composition, as by trowelling or by mold pieces placed for the purpose. As a preferred composition, an oxy-salt cement, such as an oxy-sulphate or better an oxy-chloride with a filler including cellulosic 45 material, may be employed. Magnesium oxy-chloride cement with sawdust, shavings, rice hulls, straw or the like, to which can also be added varying percentages of sand, crushed stone, infusorial earth, cinders, etc., 50 is most advantageous, such composition pro-

viding a more tenacious adhesion than bituminous compositions or other cementing agents. The oxy-cements, and more especially oxy-chloride, give a remarkably firm bond upon wood, cellulosic materials, and 55 artificial or natural stone surfaces, and such elements may be satisfactorily held to each other to withstand stresses, such that the element may be sheared within itself before the bond at the surface breaks. With the cement finally set, filler pads, felts or the like 60 4 may be spread on the floor 1, within the nailing strip 3, and the carpet 5 may then be secured by means of tacks 6 driven into the nailing strip 3. 65

A further advantage where a nail-penetrable element, that is, penetrable to nails, tacks, etc., is secured by a cementitious material including an oxy-salt, lies in the fact that magnesium oxy-sulphate, or better, oxy- 70 chloride, affords an antiseptic or preservative function in addition to its cementitious utility.

A nailing or tacking strip 3a, (Fig. 2) may be provided as suggested, being held 75 firmly in place by the cementitious adhesion to the under structure 1, and after it is firm, a top coating 7 of cement or artificial stone composition is spread in place on the main floor area adjacent, thereby raising the level 80 to the extent desired. The carpet 5 may be laid as usual and tacked to the strip 3a for instance by tacks 6.

It will thus be seen that a carpet, including 85 also linoleum or any preferred floor covering material, may thus be as readily secured in place as on a wooden floor, and while the nailing strip may be of wood, cemented to the concrete underflooring preferably by oxy- 90 chloride cementitious composition, it will more desirably ordinarily be of a composition body, the composition comprising an oxy-cement binder and a filler including cel- 95 lulosic material, and most desirably it may be cast directly in place, thus providing all advantages of necessary shaping and leveling and adapting to the requirements of any particular location.

This application is a division of my appli- 100

cation, Serial No. 163,915, filed January 27, 1927.

Other modes of applying the principle of the invention may be employed, change being made as regards the details disclosed, provided the means or steps stated in any of the following claims, or the equivalent of such be used.

I therefore particularly point out and distinctly claim as my invention:—

1. In building construction, the combination of under flooring essentially impenetrable to ordinary nails, and means for securing a carpet in place, said means comprising a nail penetrable strip at carpet receiving level of a composition made up of magnesium oxychloride and a filler including cellulosic material, the strip being cementitiously adherent to the under flooring.
  2. In building construction, the combination of under flooring essentially impenetrable to ordinary nails, and means for securing a carpet in place, said means comprising a nail penetrable strip at carpet receiving level of a molded composition, the strip being cementitiously adherent to the under flooring.
  3. In building construction, the combination of under flooring essentially impenetrable to ordinary nails, and means for securing a carpet in place, said means comprising a nail penetrable strip at carpet receiving level of a molded cementitious composition, said strip being cementitiously adherent to said under flooring.
  4. In building construction, the combination of under flooring essentially impenetrable to ordinary nails, and means for securing a carpet in place, said means comprising a nail penetrable strip at carpet receiving level of a molded cementitious composition held to said under flooring by cement.
  5. In building construction, under-flooring of material essentially impenetrable or ordinary nails, a carpet-tacking strip at carpet-receiving level on said under-flooring, and means for holding said strip to said under-flooring, said means consisting of a magnesia composition cement.
  6. In combination with a floor and a building well, a composition nailing strip cementitiously adhered to said floor and sealing the junction crevice between said floor and wall, the top surface of said strip being beveled along that margin spaced from the wall.
55. Signed by me this 7th day of April, 1928.
STANLEY H. BARROWS.
